C. W. FISLAR

DISPENSING DEVICE

Filed Dec. 11, 1926

INVENTOR,
Charles W. Fislar,
By Minturn & Minturn,
Attorneys.

Patented Dec. 6, 1927.

UNITED STATES PATENT OFFICE.

CHARLES W. FISLAR, OF INDIANAPOLIS, INDIANA.

DISPENSING DEVICE.

Application filed December 11, 1926. Serial No. 154,119.

This invention relates generally to a brush for creating a lather for use in shaving, more commonly referred to as a shaving brush, and in particular, to means for feeding soap into the brush.

The invention is described in reference to the accompanying drawing, in which

Fig. 1, is a side elevation of the brush;

Fig. 2, a vertical section through the brush;

Fig. 3, a similar vertical section showing a modification;

Fig. 4, a vertical elevation of the shaving soap nozzle;

Fig. 5, a top plan view of the soap nozzle;

Fig. 6, a transverse section through the brush on the line 6—6 in Fig. 3;

Fig. 7, a vertical section through the brush showing an internal structure modified from 20 that in Figs. 2 and 3; and

Fig. 8, a vertical section of the same modification, taken 90 degrees from that as shown in Fig. 7.

Like characters of reference indicate like 25 parts throughout the several views.

This invention is adapted to employ soap in the state commonly known as shaving cream, being of a soft consistency adapted to flow under pressure.

30 A cylindrical reservoir 10 is formed as the soap receptacle and constitutes the grip or handle of the brush. The bristles 11 are gripped in the usual hard rubber base 12 which is secured in the upper end of the 35 reservoir 10 thereby effectually closing that end.

Immediately under the base 12 is a disk 13 having a rigid nipple 14 extending upwardly therefrom, centrally through and 40 terminating slightly above the base 12, within in the bristles 11. A passage 15 extends continuously through the disk and nipple 14.

A cap 16 is screw-threadedly engaged to the lower end of the reservoir 10 so as to 45 close the lower end of the reservoir 10. A shaft 17 passes rotatably through the cap 16 and has a shoulder 18 bearing against the top side of the cap to prevent downward displacement of the shaft 17. The lower 50 end of the shaft 17 is rigidly secured within a disk 19 bearing against the under side of the cap 16, and the disk 19 has a diameter slightly larger than the diameter of the cap 16, though it may be smaller if desired.

55 In Fig. 2, the shaft 17 carries a screw-

shaft 20 above the shoulder 18, extending upwardly substantially to the under side of the disk 13. A piston 21 is screw-threadedly engaged, preferably by left-hand threads, by the shaft 20. The piston 21 carries a leather facing 22 which upon being moistened by the soft soap above, swells and contacts the walls of the reservoir in a manner to resist its rotation upon turning of the shaft 20.

The nipple 14 has a flexible, elastic rubber nozzle 23 slipped over its upper end to extend down over an enlargement on the end of the nipple so that the nozzle 23 may not slip off the nipple 14 unless expressly pulled off by force. The nozzle 23 is substantially a short piece of rubber tubing closed at its upper end, and the only opening from the nozzle 23 after it is positioned on the nipple 14 is through a puncture 24 in the upper end which is normally closed on account of the elasticity of the rubber, such puncture 24 being exactly the same opening as would be made in an automobile tire inner tube by running a needle into it.

To operate the soap feeding device, the cap 16 is unscrewed and removed from the cylinder 10 thereby removing the piston 21. Soap of the proper consistency is placed in the cylinder or reservoir. The piston 21 is run down on the shaft 20 to the shoulder 18, and the cap 16 is screwed back on the end of the cylinder 10 with the shaft 20 projecting up into the soap and the piston 21 contacting the soap from below.

By properly turning the disk 19 so as to revolve the shaft 20, the piston 21 is carried upwardly against the soap, thereby subjecting the soap to pressure, and upon sufficient pressure being created, the soap will flow 95 up the passage 15 through the nipple 14, into the nozzle 23 and stretch the rubber nozzle so that the puncture 24 is enlarged to permit the soap to flow out onto the bristles 11 until the pressure on the soap is reduced somewhat, when the elasticity of the rubber nozzle 23 will close the puncture 24 sufficiently to overcome the remaining pressure.

In practice it requires but a slight turn 105 of the handle control disk 19 to cause an ejection of just the proper amount of soap, and the unique construction of the nozzle is such that it effectually shuts off the flow 110 of the soap sharply and prevents any fur-

ther discharge until the disk 19 is further rotated. Also in practice, the soap may be furnished in convenient replacing fillers, cylindrical in form, to fit snugly into the reservoir to let the piston 21 work up through the replacing unit.

The structure above described, being that illustrated particularly in Fig. 2, is but one method of accomplishing the feeding of the soap, and many other modifications may be substituted without departing from the spirit of the invention. Two of such modifications are shown in Figs. 3, 6, 7, and 8.

Referring first to Figs. 3 and 6, the shaft 20 in Fig. 2, is replaced by a shaft 25, square in cross-section, and a piston 26 is provided to screw-threadedly engage the cylinder 27. The shaft 25 passes slidably through the piston 26 with the result that upon suitable turning of the disk 19, the shaft 25 being revolved, the piston 26 will likewise be revolved, but being screw-threadedly engaged to the cylinder 27 will travel up or down, axially of the cylinder 27. The cylinder 27 here shown is a refiller soap cylinder having threads 28 rolled into its wall and is snugly carried within the usual cylinder 10. The refiller cylinder 27 may be dispensed with if desired and the threads 28 formed directly in the reservoir wall, as in Figs. 7 and 8. By such structure, the piston is positively made to travel axially of the cylinder 10 and does not depend upon its frictional engagement with the wall of the cylinder 10 as first described.

In the structure shown in both Figs. 2 and 3, the shafts 20 or 25, must project into the soap, and while this may not be objectionable, the structure shown in Figs. 7 and 8 overcomes this feature. In the structure there shown, the piston 26' is screw-threadedly engaged to the cylinder 10, and in place of any shaft working through the piston, a series of links 30 and 31, pivotally secured one to the other and by the ends to the under side of the piston and to the shaft 17 respectively, is employed.

By rotating the disk 19, the link system is

rotated to rotate the piston 26' and as the piston 26' travels up the cylinder 10, such links approach the straight line axis to follow the piston, and conversely, as the piston is caused to travel downwardly, the links tend to fold side by side to assume substantially horizontal positions when the piston 26' is in its lowest position. The link system here shown is comparable to a folding steel rule.

While the invention is here described in one particular form, it is obvious that many changes may be made in the structural form without departing from the spirit of the invention.

I claim:

1. A soap dispenser having a soap receptacle, screw-threads formed in the internal wall of the receptacle, a piston screw-threadedly engaging said receptacle threads, a rotatable member positioned at one end of the receptacle, and a member interconnecting the under side of the piston with the said rotatable member, said interconnecting member being reduced in effective length as said piston moves toward said rotatable member.

3. In a dispensing device, a receptacle adapted to hold soap and having internal screw-threads, a piston screw-threadedly engaged in the receptacle, a rotatable member positioned at the bottom of the receptacle, and a plurality of links pivotally secured one to the other forming a foldable member attached by its ends to and between said piston and said rotatable member.

3. in a dispensing device, a receptacle adapted to hold soap and having internal screw-threads, a piston screw-threadedly engaged in the receptacle, a rotatable member positioned at the bottom of the receptacle, and a plurality of links pivotally secured one to the other forming a foldable member attached by its ends to and between said piston and said rotatable member and means limiting the flow of soap from the receptacle.

In testimony whereof I affix my signature.
CHARLES W. FISLAR.

CERTIFICATE OF CORRECTION.

Patent No. 1,651,687.

Granted December 6, 1927, to

CHARLES W. FISLAR.

It is hereby certified that error appears in the above numbered patent requiring correction as follows: In the drawings, Figs. 7 and 8, for the reference numeral "26" read "26'"; page 2, of the printed specification, line 75, for the claim numeral "3" read "2"; same page, line 84, claim 3, for the word "in" read "In"; and that the said Letters Patent should be read with these corrections therein that the same may conform to the record of the case in the Patent Office.

Signed and sealed this 10th day of January, A. D. 1928.

Seal.

**M. J. Moore,
Acting Commissioner of Patents.**
